No. 828,087.

PATENTED AUG. 7, 1906.

E. BRUNHOFF.
CIGAR CUTTER.
APPLICATION FILED MAR. 28, 1904.

UNITED STATES PATENT OFFICE.

EDWARD BRUNHOFF, OF CINCINNATI, OHIO.

CIGAR-CUTTER.

No. 828,087.

Specification of Letters Patent.

Patented Aug. 7, 1906.

Application filed March 28, 1904. Serial No. 200,276.

To all whom it may concern:

Be it known that I, EDWARD BRUNHOFF, a citizen of the United States, residing at Cincinnati, in the county of Hamilton and State of Ohio, have invented certain new and useful Improvements in Cigar-Cutters; and I do hereby declare the following to be a full, clear, and exact description of the invention, such as will enable others skilled in the art to 10 which it appertains to make and use the same.

My invention relates to improvements in cigar-cutters.

One of its objects is to provide an improved cutter mounted upon parallel arms in such manner as to give a draw cut to the knife, thereby effecting the cut with less pressure and less liability of injuring the cigar.

Another object is to provide a conduit or 20 passage to conduct the severed tips to a receptacle therefor.

Another object is to provide simple and improved means for imparting motion to the knife as the cutter is depressed.

It further consists in certain details of form, combination, and arrangement, all of which will be more fully set forth in the description of the accompanying drawings, in which—

Figure 1 is a central vertical section through my improved cutter. Fig. 2 is a top plan view, part of the frame being broken away. Fig. 3 is a section on line *v v* of Fig. 1. Fig. 4 is a bottom plan view of the cutter-head and knife. Fig. 5 is a section of the same on line *X X*, Fig. 4. Fig. 6 is a side elevation of a modification. Fig. 7 is a top plan view of the same. Figs. 8 and 9 represent detailed modifications.

Referring to Figs. 1 to 5, *A* represents the base; *B*, a dome-shaped standard, to which are pivoted the parallel arms *C D*. The projecting ends of these arms are pivoted to a shell or cutter-head *E*, which by reason of the parallel arms is held with its upper face in a substantially horizontal plane in whatever position it may occupy relative to the frame. Within the cutter-head is a concave knife *e*, pivoted at *e'* to the cutter-head. *F* represents an arm or link pivoted at *f* to the knife and at *f'* to one of the parallel arms. As shown, it is pivoted to the lower arm. It may, however, be pivoted to the upper arm, if desired, or to the standard *B*, as indicated,

respectively, in Figs. 8 and 9. A spring *G*, 55 preferably engaging link *F* at one end and the frame at the opposite end, serves to hold the parts normally in position shown in full line, Fig. 1, and to return them to this position after use. The top of the recess *b* in the standard *B* limits the upward movement of the parallel arms. The knife being concave bears only at its edges upon the under face of the cutter-head, which is pierced with one or more holes *H* to receive the cigar-tips. The 60 knife is retracted so as to uncover the tip-holes, and as the cutter-head is depressed the arm *F* pushes the knife across the tip-holes, turning on the center *e'*, which gives the cutting edge of the knife a draw cut through the 65 tip, resulting in a smooth cut through the tip and avoiding any sudden jar at the instant the tip is severed, also any tendency to pinch or mash the tip and injure the wrapper above the cut. The arm *F* by reason of the spring 70 *G* bears against the under face of the knife and holds the cutting edge of the knife against the under face of the cutter-head, thereby insuring a perfect shearing draw cut, 75 which would not occur with a space between the knife and under face of the cutter-head at the tip-holes. The parallel arms are semi-cylindrical in cross-section, so as to form a tube or passage, (see Fig. 3,) down which the tips are conducted to a receptacle *I*, formed 80 at the base of the standard *B*. A sheet-metal plate *i*, pivoted at *i'*, forms the bottom of the receptacle and can be moved on its pivot to discharge the tips from the receptacle when desired. *K* represents a detachable sheet-metal plate closing the bottom of the cutter-head and serving to direct the tips through the passage formed by the parallel arms. This plate is held in place by 85 spring-lugs *k*.

In the modification, Figs. 6 and 7, *L* represents the cutter-head provided with a knife *l*, similar to that previously described. *M* represents a tube or passage to conduct the tips to the receptacle *M'* beneath the cutter-head. *N* represents a series of parallel arms pivoted together by cross-bars *n* and secured by cross-bars *n* at *n'* and *n''*, respectively, to the frame and cutter-head. A slot *P'* in the parts *M M'* and slots in the parallel arms enable the central bars *n* to travel vertically. These central bars may, however, be omitted, if desired. A spring *P* by the engage- 90 95 100 105

ment of its free ends with arms *N* serves to normally hold the parts in the raised position. A crank-arm *p*, attached to one of the cross-bars, carries the link *p'*, which is in turn pivoted to the knife, so that when the cutter-head is depressed the knife is actuated, as previously described, to cut the tips.

I am thus enabled to provide a very simple and efficient cigar-cutter, reliable and steady in action and requiring very little power to operate it.

I do not wish to limit myself to the particular form of construction shown, as it is capable of considerable modification without departing from the principle of my invention.

Having described my invention, what I claim is—

1. In a cigar-cutter, a cutter-head provided with a tip-hole, a knife adapted to move across the tip-hole, a supporting-frame, parallel arms pivotally connected at opposite ends to said cutter-head and frame, a tip-receptacle located in the frame, and a closed passage leading from the cutter-head to said receptacle.

2. In a cigar-cutter, a cutter-head provided with a tip-hole, a knife adapted to move across the tip-hole, a frame, parallel arms pivotally connected at opposite ends to said cutter-head and frame, and forming a passage to conduct the tips from the cutter-head to a tip-receptacle located on the frame.

3. In a cigar-cutter, a frame, a cutter-head provided with a tip-hole, a knife pivoted to said head, parallel arms pivotally connecting the frame and cutter-head and a cutter-arm pivoted to the knife and adapted when the cutter-head is depressed to move the knife across the tip-hole.

4. In a cigar-cutter, a frame, a cutter-head provided with a tip-hole, a concave knife pivoted to said head, parallel arms pivotally connecting the frame and cutter-head and a cutter-arm pivoted to the knife and adapted when the cutter-head is depressed to move the knife across the tip-hole.

5. In a cigar-cutter a frame, a cutter-head provided with a tip-hole, a knife pivoted to said head, parallel arms pivotally connecting the frame and cutter-head, a cutter-arm pivoted to the knife and adapted when the cutter-head is depressed to move the knife across the tip-hole, and a spring to press the knife-arm against the knife to hold the knife close to the under face of the cutter-head.

6. In a cigar-cutter, a frame, a cutter-head provided with a tip-hole, a knife adapted to move across the tip-hole, semicylindrical parallel arms connecting and forming a passage from the cutter-head to the frame and a spring to normally hold the cutter-head in an elevated position.

7. In a cigar-cutter, a frame, a cutter-head provided with a tip-hole, a knife pivoted to the cutter-head, parallel arms pivotally con-

nnecting the cutter-head to the frame, a cutter-arm pivoted at one end to the knife and connected to one of the parallel arms, so as to force the knife across the tip-hole when the cutter-head is depressed.

8. In a device of the class described, a depressible cigar-receiving member, carrying-arms pivoted to said cigar-receiving member, a separate cutter member coöperating with said receiving member, and means actuated by one of said arms for operating the cutter member.

9. In a device of the class described, a swinging depressible cutter-head having a tip-opening, carrying-arms therefor, a cutter disconnected from said carrying-arms and movable with said head, means actuated by one of said arms for imparting a traversing movement to the cutter, and means for maintaining the cutter-head normally raised.

10. In a device of the class described, an up-and-down movable cigar-tip-receiving member, carrying-arms therefor, a cutter separate from said arms and supported by said member, means for maintaining the member normally raised, and means actuated by one of said arms for giving a traversing movement to said cutter.

11. In a device of the class described, the combination with a depressible cutter-head, and a movable cutter mounted on said head, of a plurality of arms pivoted to said cutter-head, one of said arms actuating the said mounted cutter.

12. In a device of the class described, the combination with a depressible cutter-head, and a movable cutter mounted independently of carrying-arms for said cutting-head, of a plurality of arms pivoted to said head, one of said arms having an actuating member operatively related to said cutter.

13. In a device of the class described, a depressible cutter-head, a swinging cutter thereon, and parallel arms, one of which has means for actuating the cutter; said cutter being separate from either of said parallel arms.

14. In a device of the class described, a depressible cutter-head, a cutter mounted thereon for swinging movement on a vertical axis, and carrying-arms for the head, one of which is provided with means for actuating the cutter.

15. In a cigar-cutter, a depressible cutter-head, arms pivoted to said head, a cutter supported independently of said arms, and an actuating member projecting from one of said arms into engagement with the cutter.

16. In a cigar-cutter, a cutter-head having a tip-opening, arms pivoted thereto, a rocking cutter carried by the head for movement relative to the tip-opening, and an arm pivoted independent of the cutter and operatively related thereto for moving the same on the depression of the cutter-head.

17. In a cigar-cutter, a cutter-head hav-

ing a tip-opening, arms pivoted thereto, a cutter pivoted to the head, an arm independent of the cutter and operating the latter on the depression of the head, and means for holding the head and cutter normally raised.

18. In a cigar-cutter, a cutter-head having a pressure-surface and a tip-opening, arms pivoted to said head, a cutter independent of

said arms and carried by the head, and a pivoted arm pivoted to said cutter.

In testimony whereof I have affixed my signature in presence of two witnesses.

EDWARD BRUNHOFF.
